America as represented by the Secretary of the
Navy

Application December 22, 1945, Serial No. 637,059

10 Claims. (Cl. 121—38)

1

This invention relates to hydraulic servo-motor systems more particularly for aircraft.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Objects of this invention are to provide a new, useful hydraulic servo-motor system particularly adapted for use in aircraft which combines extreme lightness with compactness of its moving parts; to provide a new and useful hydraulic servo-motor system having an extremely rapid response to the application of an energising impulse by reason of the use of high hydraulic pressure and small light weight moving parts and the low volumetric flow, hence low liquid friction, needed for the necessary power; to provide a new and useful transfer or relay valve particularly adapted for use in hydraulic servo-motor systems; to provide a new and useful hydraulic servo-motor; and, to provide a hydraulic servo-motor which will enable manifolding of at least one of the hydraulic lines where several units are served from the same pressure source, thereby to effect economies in weight and cost and facilitate installation and maintenance, and to provide a means of by-passing the action of the system servo-motor to render it safely inoperative when not in use.

Of the drawings:

Figure 1 is a somewhat diagrammatic view, with parts in section, of a typical and illustrative embodiment of a hydraulic servo-motor system in accordance with this invention, depicting the several elements of the system including the signal input control valve, the transfer or relay valve and the hydraulic servo-motor in a typical operative relationship;

Figures 2, 3 and 4 are views in section, respectively, of a typical and illustrative embodiment of a transfer or relay valve in accordance with this invention, corresponding to the transfer valve shown in Figure 1, the view Figure 2 showing the valve as it would appear with its working parts in a central or neutral position corresponding to a no-signal condition in the system of Figure 1, the views, Figures 3 and 4, showing the valve with its working parts in opposite extremes of position corresponding to maximum

2

signal conditions but of opposite sign in the system of Figure 1, the position of the working parts of the valve as shown in Figure 3 corresponding to the position of the valve parts in the showing in Figure 1; and,

Figures 5, 6 and 7 are views in section of a typical and illustrative embodiment of a hydraulic servo-motor in accordance with this invention corresponding to the servo-motor shown in Figure 1, the view, Figure 5, showing the servo-motor with its by-pass slide-valve in open position corresponding to a pressure-off condition in the system and the views, Figures 6 and 7, showing the motor with its by-pass slide-valve in a closed position corresponding to a pressure-on condition in the system and also showing the motor with its piston at opposite extremes of position in its cylinder.

In accordance with the invention there is provided a high pressure hydraulic servo-motor system including, a transfer valve, a hydraulic servo-motor and suitable means for actuating the transfer valve. The piston or other movable force member of the servo-motor, by means of which motion or a working effort is adapted to be transmitted to a lever, cable, wheel, aerodynamic control member or other member to be operated, is normally maintained in a hydraulically balanced condition by the application at all times to one working face of the piston of the full high hydraulic working pressure of the system and by the establishment, also, in the servo-motor of a balancing hydraulic force of lower unit pressure acting on the piston over the opposite, but larger area, working face of the piston.

Also, in accordance with the invention, energising of the servo-motor to effect the transmission of motion, or a working effect, by the servo-motor piston to a member to be operated is accomplished by increasing or decreasing the hydraulic pressure on the larger area working face only of the piston while maintaining the hydraulic force due to the pressure acting over the opposite working face at a constant or substantially constant value corresponding to the usual and desired system working pressure. As a result of an increase or decrease in the hydraulic pressure acting over this larger area, an unbalanced condition of the oppositely acting hydraulic forces may be obtained within the servo-motor piston against internal friction and the resistance offered by the member to be operated. Since the piston of the servo-motor is normally in a hydraulically balanced condition by reason of the oppositely acting equal hydraulic forces, a change in one of them (disregarding friction) will effect an almost instantaneous acceleration of, or application of force to, the piston by reason of the high hydraulic pressure employed, the small size and light weight of the

50
55
60

moving parts and the low volumetric flow, hence low liquid friction, needed for the necessary power. Thus, the speed or response of the servo-motor piston is unusually fast by reason of this novel combination of features.

In order to upset the balance of hydraulic forces acting on the servo-motor piston for the purpose of effecting movement of the servo-motor piston in one direction or the other, or to restore or maintain the balance of such forces in response to the unbalancing action of an external force, provision is made for increasing or decreasing at will the hydraulic pressure on the larger area working face of the piston while maintaining the pressure on the smaller area working face substantially constant. To this end and in accordance with the invention, transfer valve means are provided normally hydraulically balanced and functioning to seal the servo-motor against loss of hydraulic liquid from the larger area working face side of the servo-motor piston, the valve means being operable and so constructed and arranged however as to permit hydraulic fluid to be supplied to or discharged from the larger area side of the piston without altering or substantially altering the hydraulic pressure on the smaller area working face of the piston. The embodied transfer valve means may, if desired, be actuated by any suitable mechanical, hydraulic or electric means but is preferably fashioned so as to be pneumatically energisable by means of a suitable external control valve through the medium of which an operating pneumatic signal may be supplied to the transfer valve means to actuate it so as to obtain the desired pressure increase or decrease, or to maintain the desired balance of hydraulic forces in the servo-motor.

It will be understood that the foregoing general description and the following detailed description as well are exemplary and explanatory of the invention but are not restrictive thereof.

Referring now more particularly to the embodiment of the invention shown in the accompanying drawings, there is depicted in Figure 1 a hydraulic servo-motor system in accordance with the invention such as is particularly adapted for use in aircraft for operating the elevators, ailerons and/or rudders of the aircraft in response to controlling impulses generated by a gyroscope or other base-line indicating device. As shown, a hydraulic servo-motor 10 is operatively coupled by hydraulic lines 11 and 12 to a transfer valve 13 which in turn is operatively coupled by pneumatic lines 14 and 15 to an air signal control valve 16 having the air inlet and ejection lines 17 and 18, respectively.

The system servo-motor 10 as here preferably embodied comprises a cylinder or casing member 19, which is preferably a casting of a strong but light metal e. g. aluminium alloy, capable of withstanding high hydraulic pressures in the order, for example, of 3000 pounds per square inch. The cylinder member 19 is provided with a bore 20 containing a relatively thin cylindrical liner 21, preferably of stainless steel, offering suitable resistance to frictional wear. The liner 21 is annularly spaced from the casing 19 throughout a major portion of its length so as to provide an annular space 22 for liquid therebetween and one end of the liner is snugly lodged in a socket 23 formed by a reduced diameter section of the bore 20. The opposite end of the liner is firmly engaged by a centrally apertured gland member 24 having annular packing rings 25 and 26 by which

the gland member 24 is removably tightly sealed to the casing 19 and to piston rod 27, respectively. A split ring 28 engages the casing 19 for holding the gland member 24 in the casing. Orifices 29 in the liner 21 adjacent the gland member at suitably spaced intervals provide ports for the flow of liquid between the annular space 22 and the bore 20 and an annular shoulder 30 extends inwardly from the liner adjacent the orifices 29 to fix the extended position of the piston 31 in the bore 20 as shown in Figure 7.

The piston 31 is mounted on the piston rod 27 at one end thereof and concentrically therewith and carries annular gasket means 31' by which a sliding seal is effected between the piston and liner. The working faces 32 and 33 of the piston 31 are of unequal area by reason of piston rod 27, the piston and piston rod being proportioned to each other so that the effective area of the working face 33 is less than and in desired proportion to the effective area of the working face 32. Preferably, the area of the working face 32 is twice that of the working face 33 although other suitable proportions may be provided for as hereinafter described.

When the area of the working face 32 is twice the area of the face 33, the piston 31 will be in hydraulic balance where a unit hydraulic pressure on the face 32 is one-half the unit hydraulic pressure on the face 33. If the unit hydraulic pressure on the face 32 equals the unit hydraulic pressure on the smaller face 33, or is reduced to zero, the hydraulic force tending to move the piston to the right in the first case, and to the left in the second case, will be the same. Similarly, if the ratio of the areas is greater than 2 to 1 as, for example, 5 to 1, the piston 31 will be in hydraulic balance in such case when the unit hydraulic pressure on the large area face 32 is one-fifth the unit hydraulic pressure on the smaller area face 33. However, if the unit hydraulic pressure on the face 32 equals the unit hydraulic pressure on the smaller face 33, or is reduced to zero, the hydraulic force tending to move the piston to the right in the first case will be four times as great as that tending to move it to the left in the second case. Because of this peculiarly advantageous relationship, it becomes possible to adapt the servo-motor for use where a greater hydraulic force is required in one direction of the piston motion than in the opposite direction as, for example, in lowering and raising aircraft landing gear, wing flaps or the like, simply by establishing the necessary ratio of areas of the working faces in the first instance.

In order to maintain a fluid space between the working face 32 of the piston and the end wall 34 of the bore 20 in the fully retracted position of the piston, as shown in Figure 6, the piston is provided with a spacing member 35 which may be of cylindrical contour as shown and co-axial with the piston rod 27 and it will be apparent that the area of the end of the member constitutes a part of the area of the working face 32 of the piston.

The cylinder member 19 is preferably provided at one end with a laterally extending slide-valve housing 36 preferably integral therewith through which leads a passage 37 connecting the annular passage 22 and the bore 20 at one side of the piston 33 with a terminal port 38 in the housing surface. Another passage 39 leads directly from the bore 20 at the greater area working face side of the piston through the valve housing to a

surface port 40. It will be apparent that hydraulic liquid may be supplied through the passage 37, the passage 22 and the several ports 29 to the smaller area working face 33 of the piston and may be separately independently supplied through the passage 39 to the larger area working face 32 of the piston. The pipes 41 and 42 are connected to the cylinder member 19 at the terminal ports 40 and 38, respectively, of the passages 39 and 37, respectively, and may have a threaded connection therewith and are connected thereto in suitable fashion effective to form a liquid-tight joint under high hydraulic pressures.

Valve means are provided for automatically connecting the bore spaces on opposite sides of the piston 31 to each other when the hydraulic pressure on the working face 33 of the piston falls to a selected minimum value so that the piston may be freely slideable in its cylinder. As here preferably embodied, a slide valve 41 having pistons 43 and 46 is reciprocably mounted in a valve chamber 42 in the valve housing 36, one end of the valve chamber connecting with the liquid passage 37 so that hydraulic pressure of the liquid in the passage 37 may act against the valve piston 43 to force the valve to the valve-closed position shown in Figures 1, 6 and 7. The valve piston 43, in the valve-closed position, as shown in Figures 1, 6 and 7, covers one end of a by-pass passage 44 whose other end terminates in the passage 37. As hydraulic pressure on the piston 43 is reduced, the valve 41 is moved by a spring 45, acting against a piston 46 at the other end of the valve, to a valve-open position, as shown in Figure 5. The pistons 43 and 46 are spacedly connected by a stem member 47 of reduced diameter providing an annular space 48 therebetween forming in effect an enlarged chamber portion in the passage 39. The piston 46 is provided with suitable gasket means 49 forming a sliding seal with the wall of the valve chamber 42 against leakage from the valve housing around the valve spring retaining member 50. An annular shoulder 51 extending inwardly from the valve housing 36 into the valve chamber 42 provides a limit stop against which the piston 43 abuts in the valve-open position, as shown in Figure 5.

It will be apparent that starting with the pressure-off condition shown in Figure 5, hydraulic liquid supplied to the servo-motor via the passages 37 and 39 will fill the annular passage 22 and the bore 23. The liquid entering through the passage 37 acts against the piston 43 to overcome the force of the spring 45 with the result that the valve 41 will be moved to the valve-closed position shown in Figures 6 and 7 thus blocking the by-pass passage 44 which enables the movement of the piston in the pressure-off condition. A balance of the hydraulic forces acting on the working faces 32 and 33 of the piston 31 may be achieved by suitably proportioning the pressures on the opposite side of the piston to each other to compensate for the difference in area of the working faces. Preferably, the area of the working face 32 of the piston 31 is twice that of the working face 33 and the unit hydraulic pressure of the liquid supplied through the passage 37 is preferably twice that of the liquid supplied through the passage 39. It will be apparent that by increasing the unit pressure of the liquid entering through the passage 39, the piston 31 may be moved from the position shown in Figure 6 to the position shown in Figure 7, the

unit pressure of the hydraulic liquid in the opposite side of the piston being maintained constant. Similarly, by reducing the unit pressure on the working face 32, the piston may be moved from right to left as viewed in Figure 7. It will therefore be clearly apparent that because the unit pressure on the high pressure side of the servomotor is maintained constant, a number of servomotor units may be connected together in a bank for individual operation by manifolding the high pressure side of each to a common header and supplying the low pressure side of each hydraulic unit with hydraulic liquid by a separate line to each unit. In this way, the piping required for the operation of a plurality of servo-motor units may be substantially reduced with concomitant savings in weight and cost and manifest simplification of installation and maintenance problems.

For the purpose of mounting the unit with a view to its use in aircraft, so as to be self-aligning, the cylinder member 19 may be provided with an eye or lug member 52 as best shown in Figure 5, which may threadedly engage the cylinder member 19 at one end thereof and is provided with a self-aligning ball bearing fitting 53 for attaching the unit to a mounting shaft of the aircraft structure. Similarly, the piston rod 27 may terminate in a removable fitting 54 threadedly engaging the rod and provided with a self-aligning ball bearing unit 55 for coupling the piston rod to a rock-shaft or other member to be operated.

The transfer valve 43 as here preferably embodied comprises front and rear body sections 60 and 61 respectively, as are best seen in Figures 1 to 4 inclusive. The respective body sections are firmly but removably secured to each other as by means of a circular row of screws 62 passing through one section into threaded engagement with the other section. The opposing faces of the body sections are fashioned to provide a valve chamber 63, preferably cylindrical, within which is disposed in part a normally hydraulically balanced hydraulic valve member 64. The valve member 64 is shown in its neutral position in Figure 2 and in extreme oppositely displaced positions in Figures 3 and 4, the position shown in Figure 3 corresponding to that of Figure 1, as will be explained more fully hereinafter.

The valve member 64 is preferably provided with oppositely extending and preferably co-axially aligned piston members 65 and 66, preferably of cylindrical contour, which are freely, slidably received in preferably co-axially aligned valve seats or cylinders 67 and 68, respectively, of complementary contour and diameter provided in the valve body sections 60 and 61, respectively. The end faces 69 and 70 of the piston members 65 and 66, respectively, constitute the working faces of the pistons and in accordance with the invention, these faces are of unequal areas corresponding to the ratio of areas of the working faces 32 and 33 of the servo-motor piston 31. To this end, the area of the working face 69 of the valve piston member 65 is larger than the area of the working face 70 of the valve piston member 66, the ratio of areas preferably being in the order of two to one as in the case of the servomotor 19. Hydraulic pressure liquid is adapted to be supplied to the working faces 69 and 70 through passages 71 and 72, respectively, provided in the body sections 60 and 61, respectively. In accordance with the invention, hydraulic liquid may be supplied to the passage 71 from the

pipe 11 and may be supplied to the passage 72 from the pipe 12 which latter is adapted to be supplied with the high pressure hydraulic liquid through a main feed pipe 73 from a high pressure pump or high pressure liquid reservoir (not shown).

The valve member 64 additionally comprises means for shifting the valve member in either direction from its neutral position in response to an external energising force or impulse as, for example, from the signal control valve 16. As here preferably embodied, a series of highly flexible, fluid-impermeable diaphragm members 75, 76 and 77 are secured concentrically of each to the valve member and in axially spaced relation therealong and are fixedly secured at their respective marginal portions in relation to the valve body sections 60 and 61 as will appear more fully hereinafter. More specifically, the diaphragm member 75, preferably of circular contour, is clamped between opposing circular flange members 78 and 79 of the valve member and midway between the diaphragm members 76 and 77. The flange clamping members 78 and 79 may be secured to each other and to the diaphragm member 75 by screws or rivets (not shown) or may be adhesively bonded to the diaphragm member 75. Each flange member is preferably formed integrally with a concentric axially extending clamping boss, the flange member 78 having the boss 80 and the flange member 79 having the boss 81. The bosses 80 and 81 are also preferably of cylindrical contour and disposed to co-act with valve piston heads 82 and 83, respectively, to clamp the diaphragm members 76 and 77 between them. Thus, the boss 80 and piston head 82 clamp the diaphragm member 76 between them, being coupled to each other and to the diaphragm member by means of screws or rivets (not shown) or preferably by adhesive bonding to the diaphragm members with which they are concentric. The boss 81, diaphragm member 77 and piston head 83 similarly co-act. Thus, the valve member 64 will be seen to be composed of a plurality of separate elements correlated and coupled to each other and integrated into a unit reciprocable in either direction in the valve piston seats 67 and 68 and the valve chamber 63.

The valve chamber 63 is preferably of cylindrical contour having parallel end walls 84 and 85 recessed to form stepped, concentric, preferably cylindrical wells 86 and 87, respectively, for accommodating the valve piston heads 82 and 83, respectively, as the valve member is displaced to right or left from its neutral position. The extent of axial movement of the valve member 64 is confined to fixed limits by the provision of an annular slot 88 extending radially outwardly from the valve chamber into which extend the valve flanges 78 and 79 and which is partitioned centrally by the diaphragm member 75. The opposite parallel end walls 89 and 90 of the slot provide opposing abutments against which the flange members 78 and 79 may contact as the valve member 64 is displaced to right or left and thus serve to limit the displacement of the valve member in accordance with the predetermined operating characteristics of the valve.

The diaphragm member 75 is received at its outer circumferential margin between the body sections 60 and 61 so as to be held securely thereby and therebetween. Likewise, the diaphragm members 76 and 77 of smaller outside diameter are clamped at their outer circumfer-

ential margins to the body sections 60 and 61, respectively, as by means of annular clamping rings 91 and 92, respectively.

It will be apparent that the diaphragms 76 and 77 form with the central diaphragm 75, a pair of hermetically sealed chambers 93 and 94 from which passages 95 and 96, respectively, lead to the outer surface of the body sections 60 and 61, respectively, where they are sealingly connected to air lines 14 and 15, respectively, of the signal control valve 16.

Likewise, the diaphragm members 76 and 77 form with the body sections 60 and 61, respectively, a pair of hermetically sealed compartments 97 and 98 which are connected to each other by a passage 99 leading through the body sections and to the outer surface of the body section 60 where connection is made to a hydraulic liquid return line 100 leading to the liquid sump or reservoir (not shown) of the hydraulic system. Hydraulic liquid which forces its way past the valve pistons 65 and 66 under the hydraulic pressures employed, discharges into the drainage compartments 97 and 98, respectively, from which it may return to the system reservoir through the pipe 100.

The valve piston cylinders 67 and 68 are provided with ports 101 and 102, respectively, both of which are normally just covered and closed by the valve pistons 65 and 66 when the valve member 64 is in the neutral position shown in Figure 2. The ports 101 and 102 are suitably located along the length of the respective cylinders 67 and 68 and the valve piston members 65 and 66 are of such length that as the valve member 64 is moved in one direction or the other from the neutral position, it will immediately start to uncover one or the other of the ports 101 and 102, depending upon the direction it is moved. The port 101 is connected by a passage 103 to the return passage 99 and thence to the system sump by the pipe 100. The port 102 is connected by a bleed passage 104 to the valve piston cylinder 67 at the working face end of the valve piston 65. Thus, as shown in Figure 3, movement of the valve member 64 to the right from the neutral position shown in Figure 2, will uncover the port 102 in part or in whole and result in the formation of a continuous passage for liquid from the entrance port of the passage 72, through the passage 104 to the exit port of the passage 71. Hence, hydraulic liquid supplied to the passage 72 through the pipes 73 and 12 can not only act against the working face 70 of the piston member 66, but can also act against the relatively large area working face 69 of the valve piston member 65 and against the relatively large area working face 32 of the servo-motor piston 31, so long as the port 102 is uncovered. Similarly, when the valve member 64 is moved from its neutral position to the left, as shown in Figure 4, the port 101 will be uncovered in whole or in part and result in the formation of a continuous liquid passage from the entrance port of the liquid passage 71 through the passage 103 to the exit port of the passage 99. Hence, hydraulic liquid supplied to the passage 71 by the pipe 11 may flow directly to the system return sump through the return line 100.

The signal control valve 16 may be of any suitable type operative to establish a differential pneumatic pressure through the pipes 14 and 15 in the chambers 93-94 for effecting a movement of the valve member 64 in the desired direction and of the desired magnitude. As here prefer-

ably embodied, a vane 110 shown in dotted lines is mounted in a casing 111 for angular movement in either direction from a neutral position in alignment with the air inlet and eduction pipes 17 and 18. Preferably, the pipe 18 is connected to a vacuum pump (not shown) and the pipe 17 is open to the atmosphere, although it is obvious that air under pressure may be supplied to the casing through the pipe 17, and the pipe 18 then arranged to discharge to the atmosphere. With the vane 110 in the dotted line position shown, the chamber 94 will be subject to a greater fluid pressure than the chamber 93 and, by reason of the pressure difference acting on the diaphragm member 75, the valve member 64 will be caused to move to the right as shown in Figures 1 and 3. Obviously, the valve member may be displaced in the opposite direction from its neutral position by angular movement of the vane in the opposite direction from its neutral position. In either case, the magnitude of the initial displacement of the valve member 64 will be proportioned in part to the duration and amount of displacement of the vane 110, the vane in turn being controlled manually or automatically, as for example, by precession of a displacement or rate gyroscope, or a combination thereof, in response to a course and/or attitude change of a dirigible vehicle.

In the operation of the hydraulic servo-motor shown in Figure 1, the system is first filled with hydraulic liquid in the required amount with the liquid in the supply pipe 73 at the desired working pressure of, for example, 1000-3000 pounds per square inch. Under these conditions, the unit hydraulic pressure exerted by the liquid on the smaller area working face 33 of the servo-motor piston 31 and on the smaller area working face 70 of the valve piston member 64 is the same. The resulting hydraulic force acting on the working face 33 of the piston 31 is balanced by an equal and opposite hydraulic force on the working face 32; but because of the larger area of the working face 32, the unit hydraulic pressure of the liquid acting on the working face 32 will be at a lower value of, preferably, half the unit hydraulic pressure on the opposite side of the piston. The same condition will exist with respect to the unit hydraulic pressure on the working face 69 of the valve piston member 65. Hence, the servo-motor piston 31 and the valve member 64 will be in hydraulic balance, with the piston 31 at rest and the valve member 64 at rest in the neutral position shown in Figure 2. Assuming now for example that the vane 110 of the signal control valve 16 is displaced from a neutral position in alignment with the ports of the air lines 17 and 18 to a position such as is shown in Figure 1, the suction applied through the pipe 18 will be communicated to the chamber 93 of the transfer valve and atmospheric or substantially atmospheric pressure will be established in the chamber 94. As a consequence of the differential pressure, the valve member 64 will be displaced to the right and, assuming the differential control signal to be of sufficient strength, to the extreme position shown in Figures 1 and 3. The movement of the valve member will result in the uncovering of the bleed port 102 and permit the full system pressure to be applied through the passage 104 to the working face 69 of the valve piston member and to the corresponding working face 32 of the servo-motor piston 31. The resulting unbalanced hydraulic force acting on the working face 32 of the piston 31 will substantially instantly cause the piston 31 to move rapidly to the right as viewed in Figure 1 against

the resistance offered by whatever member to which the piston rod 27 is connected. If that member be, for example, the rudder of an aircraft in flight, the rudder will be displaced until the dynamic forces acting thereon attain a value at which the unbalanced hydraulic force acting on the working face 32 is balanced thereby and the piston 31 thereby brought to rest.

The pneumatic displacement force which caused the initial displacement of the valve member 64 is opposed and balanced by the opposing hydraulic force resulting from the increase in hydraulic pressure on the working face 69 of the valve piston member 65 as the port 102 is uncovered. This excess of hydraulic force on the working face 69 will remain, even though the servo-motor piston 31 has come to rest under the balanced forces, until the differential signal pressure in the chambers 93-94 is caused to decay as by initiating restoration of the vane 110 toward its no-signal position. As the signal is caused to decay, the pneumatic displacement force decreases, the balance between the displacement force and the excess of hydraulic force on the working face 69 is upset and the valve member 64 is moved hydraulically toward its neutral position. When the signal has fully decayed, the valve member will have returned to its neutral position, the port 102 will have been covered again and the valve member 64 will be in the neutral position shown in Figure 2. It will be remembered, however, that it was assumed that the piston 31 in its initial displacement was resisted by the dynamic forces acting on an aircraft control member (not shown). This resistive force added to the hydraulic force acting on the working face 33 was balanced by the increased hydraulic force acting on the working face 32 of the piston resulting from the application of the system pressure to the working face 32. Hence, as the hydraulic pressure on the working face 32 is decreased by the covering of the port 102, the dynamic pressure exerted by the control member will continue to act through the hydraulic liquid in the pipe 11 on the working face 69 of the valve piston member 65 and cause the valve member 64 to move to the left, as viewed in Figure 4, thus uncovering the port 101. The hydraulic liquid may in consequence flow through the passages 103, 99 and the system return line 100 to the sump or reservoir not shown to relieve the excess of hydraulic pressure on the working face 69. As the resistive force of the control member on the piston 31 decays through return of the control member to a neutral position, the decreasing unbalanced hydraulic force acting on the piston member 65 permits the valve member 64 to return to its normal neutral condition with the hydraulic forces on the valve member 64 and the piston member 31 in balance.

It will therefore be apparent that displacement of the valve member 64 to the left, as shown in Figure 4, by actuation of the signal vane 110 in a clockwise direction, as viewed in Figure 1, will uncover the port 101 and thus relieve the balancing hydraulic pressure of the liquid on the working face 32 of the piston. So long as this condition is maintained, the full system pressure acting on the working face 33 will function to move the piston 31 to the left, as viewed in Figure 6 until the hydraulic pressure differential is balanced as before by the dynamic pressure acting on the control member to which the piston rod 27 is connected. When this condition is attained, the piston 31 will come to rest and remain at rest as the valve member 64 is returned to its

11

neutral position by a decay of the control valve signal. As the pressure on the working face 67 under these conditions will be less than the pressure on the working face 70, the valve member 64 will be automatically displaced to the right, as viewed in Figure 3, the port 102 uncovered and the hydraulic pressure acting on the working face 32 built up. As it builds up, the dynamic force on the control member will return the latter to its neutral position, and hydraulic balance will again be achieved in respect of the piston 31 and valve member 64.

It will be obvious that if the piston 21 be connected to a member offering only frictional resistance to movement, the movement will continue within the limit of movement of the piston 31 until the valve member is returned to its normal neutral position. Return of the piston to its starting position may be effected by movement of the valve member in the opposite direction.

Although the servo-motor shown is of the reciprocating piston-cylinder type, it will be obvious that the piston may be a vane affixed to a shaft journaled for limited angular movement in a cylindrical casing so that the movement of the vane by unbalanced hydraulic forces may rotate the shaft directly. In such case, the shaft may be that upon which a rudder, elevator, aileron, or other control member is mounted, thereby eliminating, or reducing in substantial measure, multiple links, cables, sheaves, push rods and such motion transmitting devices between the servo-motor and the control member and effecting advantageous economies in cost, weight maintenance and the like.

The invention in its broader aspects is not limited to the specific mechanisms shown and described but departures may be made therefrom within the scope of the accompanying claims without departing from the principles of the invention and without sacrificing its chief advantage.

What I claim is:

1. In a hydraulic servo-motor system for use with a differential pneumatic signal generator and having a source of hydraulic liquid under high pressure and a sump; the combination of a valve piston and a servo-motor piston each having a pair of working faces of unequal area, the ratio of areas of the pairs of working faces being substantially the same; hydraulic circuit forming means including a pair of cylinder means slidably receiving said pistons respectively, said circuit forming means comprising a high pressure leg between the pair of working faces of correspondingly small area having an induction port through which hydraulic liquid is adapted to be supplied to said leg from said high pressure source, a low pressure leg connecting the pair of working faces of correspondingly large area and having an eduction port normally covered by said valve piston through which hydraulic liquid is adapted to be discharged to said sump, and a pressure-equalizing leg for connecting the high and low pressure legs to each other having a terminus in said low pressure leg and an entrance port in said high pressure leg, said entrance port being normally covered by said valve piston; and means responsive to the differential pneumatic signal for shifting said valve piston in one direction in its associated cylinder means to uncover said entrance port of said pressure-equalizing leg and for shifting said valve piston in the opposite di-

12

rection to uncover the eduction port of said low pressure leg, said valve piston shifting means including a pneumatically actuated flexible diaphragm attached to said valve piston.

5. The hydraulic servo-motor system of claim 1 in which said valve piston shifting means further includes a signal control valve, duct means connecting said valve and said pneumatically actuated diaphragm, said signal control valve establishing a differential pneumatic pressure on opposite sides of said diaphragm in response to the differential signal.

3. In a hydraulic servo-motor system having a source of hydraulic liquid under high pressure and a low pressure sump, the combination of a servo-motor having a piston with working faces of unequal area, a transfer valve having a valve piston with working faces of unequal area and of the same ratio of areas as the working faces of said servo-motor piston, separate hydraulic legs between the corresponding pairs of working faces, a pressure-equalizing leg in said transfer valve for connecting said legs to each other at will and a discharge port in the hydraulic leg between the large area pair of working faces, said pressure equalizing leg and said discharge port being normally closed by said valve piston and selectively openable thereby, conduit means connecting said source of high pressure hydraulic liquid with the hydraulic leg between the small area working faces and connecting said eduction port to said sump, said transfer valve including a pair of coaxial cylinder portions of unequal diameter and an intermediate cylinder portion of a larger diameter than said coaxial portions and connecting the latter, said valve piston traversing said intermediate portion and having oppositely extending piston members slidably received in and complementary to said coaxial portions, and pneumatically actuated piston shifting means mounted in said intermediate portion and attached to said oppositely extending piston members.

4. A valve comprising a cylinder portion, a piston therein having a pair of opposed working faces of unequal area, separate ducts for supplying hydraulic liquid to said working faces, a duct for connecting said first mentioned ducts, and a duct for venting liquid from one of said supply ducts, said connecting and venting ducts being normally closed by said piston; and, pneumatically actuated means for moving said piston in opposite directions to selectively open one or the other of said connecting and venting ducts, said last named means including a flexible diaphragm attached to said valve piston.

5. A transfer valve comprising a body portion having cylinders of unequal diameter connected by a seepage chamber, a pair of piston members complementary to and slidably received in said cylinders, flexible diaphragm members traversing said chamber between said piston members and said body portion and dividing said chamber into pairs of separate compartments, the compartments of one of said pairs serving to collect seepage liquid from said cylinders, air ducts for establishing a pressure differential in the compartments of the other of said pairs, a duct for educting seepage hydraulic liquid from said collecting compartments; separate ducts for supplying hydraulic liquid separately to each of said cylinders, a pressure equalizing duct for connecting said supply ducts at will, and a venting duct for venting the larger diameter cylinder and its supply duct through said body portion, said

13

pressure equalizing duct and said venting duct being normally closed by said piston members.

6. A transfer valve comprising a body portion having coaxial cylinders of unequal diameter connected by a chamber of substantially larger diameter, each said cylinder having a port in its cylinder wall, a valve piston comprising a pair of coaxial piston members each complementary to and slidably received in one of said cylinders and covering the port therein, flexible diaphragm members in said chamber flexibly connecting said body portion and said valve piston and dividing said chamber into a pair of air compartments for effecting reciprocation of said valve member by differential pressure and a pair of intercommunicating seepage compartments for receiving seepage hydraulic fluid discharged from said cylinders, said air compartments communicating through separate ducts with separate openings in the surface of said body portion, separate ducts for supplying hydraulic liquid separately to the respective cylinders, a pressure-equalizing duct connecting the port in the smaller diameter cylinder with the larger cylinder supply duct, and a vent duct connecting the port in the larger cylinder with a separate opening in the surface of said body portion and providing communication between said opening and said seepage compartments.

7. A valve comprising a body member having a chamber therein, said chamber portion including a pair of spaced cylinder means of unequal diameter connected by a larger intermediate cylinder means, a valve piston in said chamber having a pair of oppositely extending piston members complementary to and slidably received in said spaced cylinder portions, said piston members having unequal working areas, separate ducts for supplying hydraulic fluid under high and low pressures, respectively, to the small and large area working faces, respectively, a duct for equalizing the pressures in said supply ducts, a duct for releasing the pressure in said low pressure duct, said pressure equalizing and releasing ducts being normally closed by said piston, and pneumatically operated means mounted in said intermediate cylinder means and operatively connected to said valve piston for moving said piston members to selectively uncover either one or the other of said pressure equalizing and releasing ducts.

8. In a hydraulic servo-motor system for use with a differential pneumatic signal generator and having a source of hydraulic fluid under high pressure and a sump; the combination of a valve piston and a servo-motor piston each having a pair of working faces of unequal area, the ratio of areas of the pairs of working faces being substantially the same, hydraulic circuit forming means including a pair of cylinder means slidably receiving each of said pistons, said circuit forming means further including a high pressure leg between the pair of working faces of correspondingly small area having an induction port through which hydraulic liquid is adapted to be supplied to said leg from said high pressure source, a low pressure leg connecting the pair of working faces of correspondingly large area and having an eduction port normally covered by said valve piston through which hydraulic fluid 70

14

is adapted to be discharged to said sump, and a pressure equalizing leg for connecting the high and low pressure legs to each other having a terminus in said low pressure leg and an entrance port in said high pressure leg, said entrance port being normally covered by said valve piston, and pneumatically actuated valve shifting means mounted on said valve piston intermediate the working faces thereof, responsive to the differential pneumatic signal, for shifting said valve piston members in one direction to uncover said entrance port of said pressure equalizing leg and for shifting said valve piston members in the opposite direction to uncover the eduction port of said low pressure leg.

9. In a servo-motor system having a source of hydraulic fluid under high pressure and a sump, a servo-motor including a piston slidably mounted in a cylinder, said piston having a pair of working faces of unequal area, high pressure conduit means connecting said high pressure source with the smaller of said working faces, low pressure conduit means connecting said sump and the larger of said working faces, pressure equalizing conduit means connecting said high pressure conduit means and said low pressure conduit means, first-mentioned valve means mounted in and normally closing said pressure equalizing leg to prevent communication of the low pressure fluid and high pressure fluid, second-mentioned valve means in said low pressure conduit means to normally prevent the fluid therein from flowing to said sump, and pneumatically actuated means operatively connected to said first and second mentioned valve means for selectively opening or closing said first and second-mentioned valve means, so that when the first-mentioned valve means is opened the pressure in said low pressure conduit means equalizes with that in said high pressure conduit means thus providing an unbalance in the forces applied to said unequal area working faces causing the piston to move in one direction, and when the first-mentioned valve means is closed and the second-mentioned valve means is opened the high pressure fluid in said low pressure conduit means is permitted to communicate with said sump thus decreasing the force differential on said unequal working faces causing said piston to move in the opposite direction.

10. The servo-motor system of claim 9 wherein said pneumatically actuated means includes a flexible diaphragm connected to said valve means and mounted in a cylinder intermediate the ends thereof, and a signal control valve for supplying a differential pneumatic pressure to opposite sides of said flexible diaphragm.

THEODORE W. KENYON.
